UNITED STATES PATENT OFFICE.

MURRAY CORRINGTON, OF NEW YORK, N. Y.

ELECTRO-MECHANICAL BLOCK-SIGNALING APPARATUS.

SPECIFICATION forming part of Letters Patent No. 496,041, dated April 25, 1893.

Application filed April 26, 1892. Serial No. 430,730. (No model.)

To all whom it may concern:

Be it known that I, MURRAY CORRINGTON, a citizen of the United States of America, residing at New York, in the county and State of New York, have invented certain new and useful Improvements in Electro-Mechanical Block-Signaling Apparatus for Railways, of which the following is a specification.

My invention relates to an organization of signaling apparatus commonly termed the "block system," the essential feature of which consists in the arbitrary division of the line of a railway into a series of successive sections, of convenient length, according to the necessities of the traffic, at the entrance to and exit from which sections signaling points are established, such sections being technically termed "blocks." The fundamental principle governing the operation of such a "block system" is that all trains passing in succession in the same direction along the railway shall be so controlled or directed by the indications of the signals exhibited at or near the entrance to each block, that only a single train shall be permitted to be within the limits of any one section at the same time.

My invention comprises mechanism whereby upon the entrance of a locomotive or train into a block-section, a visual signal denoting "line blocked" is exhibited at the entrance of said block, either by a signalman, or by the automatic action of the train itself, and such signal is furthermore provided with a locking device, which automatically secures it in such position until the train whose rear is protected by it has made its exit from the distant end of the block, and has passed under the protection of the next signal in the series. The first mentioned signal may then be unlocked or released, and moved into position to denote "line clear" by the manual operation of the signalman. In order to accomplish this, however, the signalman is compelled, by the organization of the apparatus, to move his signal-operating lever into a certain predetermined position. But by the act of doing this, the apparatus becomes interlocked with an electro-mechanical detent, from which it can be released only by the action of an electrical current transmitted from the next signaling point in the direction in which the train moves. Hence each signal, when in po-

sition indicating "line blocked," is doubly secured, first by a mechanical lock, and second by an electro-mechanical lock.

55

My invention also comprises means of locking the signal operating lever in a position indicating "line clear," except when a train is about to enter the block, together with a visual indicator by means of which the signalman at each signaling point is advised of the presence of a train on the adjacent block in either direction.

In the accompanying drawings, Figure 1 is a diagram showing in outline the essential portions of the apparatus at three adjacent and consecutive signal stations upon the line of a double-track railway, with the electrical connections between them. Fig. 2 is a side elevation (partly in section), of the apparatus whereby the signal may be manually operated by the signalman; and Fig. 2^a is a detail view in cross-section, of a portion of the same. Fig. 3 is a front elevation of a portion of the apparatus shown in Fig. 2, showing the visual indicator. Fig. 4 is a plan illustrating the operation of the track-instrument by which the signal is automatically caused to be exhibited by the action of a moving train. Fig. 5 is a side elevation, and Fig. 6 a front elevation of the same, the latter showing the signal. Figs. 7 and 8 show a track-instrument, and the locking apparatus of the hand-lever, in elevation and plan respectively.

Referring first to Figs. 4, 5 and 6, A represents a semaphore signal of the form commonly used on railways, consisting of an arm pivoted to an upright post alongside the track of the railway, and when in the position shown in the figure, indicating "go on" or "line clear" to the engineer of an approaching train, but when desired to signify "stop" or "line blocked," is raised to a horizontal position by drawing down the vertical rod *a*. This movement is effected by a mechanical connection with an inclined treadle, consisting of one or more bars *B' B'*, which lie nearly horizontally in a vertical plane which is parallel to and alongside one of the rails of the track *D*, being jointed or pivoted thereto at their outer ends as seen at *b* and *b'* (Fig. 6). The inner ends of the treadle-bars *B' B'* are pivoted to each other, and to a short vertical bar *C*, at *b'*, which vertical bar, at its

lower end c , slides through a guide c' . The treadle-bars normally lie at a small angle with each other as shown, and their inner ends are raised a little above the top of the rail D , as best seen in Fig. 6. A bell-crank lever C' is pivoted at one end to the vertical bar C and turns upon pivot c^3 , while its other end is jointed by a link C^2 to the horizontal sliding rod a^3 , which may extend any required distance to another pivoted bell-crank a^2 which communicates motion to the rod a' and semaphore A . The treadle-bars B' B' may be depressed, so as to place the semaphore A in a position indicating "stop," in either one of two ways, namely, by the manual act of the signalman, or by the passage of a moving train. The treadle-bars B' B' and the semaphore A are normally maintained in the position shown in Fig. 6, mainly by the action of a strong spring b^3 , which depresses the longer arm of a transverse lever B . The shorter end of this lever, which is pivoted at b^2 , engages at c^2 with the vertically moving bar C which receives its movement from the treadle-bars, while its opposite end bears against and rests upon a cam E , which is fixed upon the same axis e with a toothed pinion E' . A horizontal rod F carries at its extremity a rack F' , which engages with the pinion E' and thus serves to rotate the cam E .

In Fig. 2, F^5 is a hand-lever, by means of which the signalman may actuate, among other things, the rod F above referred to. This lever is pivoted at f' to an upright standard upon the floor of the signal-cabin, and its short end is jointed to a rod F^4 which takes hold of a bell-crank lever F^3 which is pivoted at f , and whose other arm is jointed to the rod F by which the cam E is rotated, as hereinbefore explained. Hence it will be understood that the signalman, by moving the hand-lever F^5 from an intermediate position, as shown in full lines in Fig. 2, in the direction indicated by the lower arrow in the same figure, will raise the long end of the lever B , depressing the treadle-bars B' B' , and raising the semaphore A into a position indicating "stop." The same result will be effected if the treadle-bars are depressed by the weight or impact of a passing train.

When the semaphore A is to be displayed by the mechanical impact of a moving train upon the treadle-bars B' B' , it may happen that some of the connecting parts would be broken in case the connections between said treadle-bars and the semaphore are made rigid. In order to obviate this difficulty, the stout spring C^3 is placed upon the rod a^3 , and bears with one end against a shoulder at the end of said rod while its other end bears against the sliding block C upon said rod, which block is connected to the link C^2 . Where the wheels of the moving train strike and depress the treadle-bars, the spring acts to take up the power of the sudden blow upon said treadle-bars. Said spring is compressed in the first instance, by the block C^4 moving

along the rod a^3 , and, as said treadle-bars are locked in the position to which they have been moved by the train, as will be fully explained hereinafter, the recoil of the spring C^3 , acting upon the rod a^3 , will cause said semaphore to be raised to the proper position.

When movement above referred to has been effected, either manually or automatically, the lever B , as well as the semaphore A and all the parts dependent thereupon, are prevented from resuming their normal positions by a stop G , which being forced outwardly by a strong spring g , slips under the raised end of the lever B , thus effectually locking it in position to display the signal "Line blocked," even after the actuating force has been withdrawn. Thus it will be understood that upon the passage of every train, the semaphore A is at once put in position to denote "line blocked" to protect its rear, and that even the signalman himself is powerless to remove it, except by withdrawing the locking stop G , which can only be done under certain prescribed conditions as hereinafter more fully explained.

The movements of the hand-lever F^5 , by which the signalman changes the indications of the semaphore A , are controlled by two independent locking devices, one of which is unlocked by the moving train while passing the signaling point, and the other by an electric current, transmitted at the proper time from the next station in the direction toward which the train is moving.

The hand-lever F^5 is mounted in and supported by a standard, fitted with a quadrant H in which are formed two concentric grooves or channels h^3 and h^4 , communicating with each other at both ends by transverse channels h^9 and h^{10} . At the bottom of each of these transverse channels are recesses h' h'' . An angular pin or projection h , which takes into the channels above referred to, is fixed upon the locking rod f^3 , which moves longitudinally in guides attached to the hand-lever F^5 and is actuated by a hand-piece f^2 . The hand-lever F^5 is shown in Fig. 2 in full lines in an intermediate position, as when passing from the position indicating "go on" to the position indicating "stop." If it were desired, for instance, to move the hand-lever into the position corresponding with the indication "go on" or "line clear," as indicated by dotted lines in Fig. 2, this could not be done directly, as the path of the pin h would be blocked by the pivoted gravitating stop h^8 . The pin h must therefore first be moved into the transverse channel h^{10} , (passing the gravity stop h^5 on the way,) thence up into the upper channel h^3 (provided the stop I has been released, as hereinafter explained) and thence past the gravity stops h^6 and h^7 , coming to rest at length in the recess h' . It will be understood from this description, therefore, that when the pin h is at rest in the recess h' , the semaphore A must of necessity be in a position indicating "stop," or "line

blocked," and that the signalman cannot possibly change this indication by moving the hand-lever unless the stop I is free to yield to the movement of the pin h. So also when 5 the pin h has been moved into the recess h', and the semaphore A has been brought to a corresponding position, indicating "go on," or "line clear," thus admitting the train to enter the block-section, I provide means 10 whereby the hand-lever F⁵ and the semaphore A are securely locked in that position except while a train is actually passing the signaling point at the entrance of the block. It is to be understood that the semaphore signals are 15 designed primarily to be operated by the signalman, and that the automatic apparatus for actuating them is provided merely as an additional safeguard, so that the signal will automatically be moved into position to block 20 the line, in case the signalman, from any cause, should fail to do so.

The function of the locking device referred to, is to prevent the possibility of the signalman moving his hand-lever into a position 25 which will permit an electric impulse to be transmitted to clear the signal at the entrance of the block at station last passed, until the train has passed completely out of the block which is guarded thereby.

30 The operation of this part of the mechanism is as follows:—The forward position of the hand-lever corresponds with the indication "line blocked," and the backward position (shown in dotted lines) with the indication "line clear." When the block in advance 35 of any station has been cleared, and the hand-lever has been moved into its backward position and locked there, the corresponding 40 semaphore must indicate "line clear." The rules of operation will instruct the signalman, upon the near approach of a train, to grasp his hand-lever and be ready to move it into its forward or blocking position. As soon as 45 the unlocking mechanism, (which should be located about twenty-five yards in advance of the track-instrument for operating the signals) is actuated by the train, the signal A is shifted into position to indicate "line blocked" for the protection of the rear of the 50 train. By thus ordinarily operating the semaphore by hand, the shock, and resulting wear and tear, necessarily resulting from the operation of the signal by the impact of a rapidly moving train, is avoided. In case the 55 signalman for any reason fails to perform his duty, the signal is nevertheless actuated by the train so as to indicate "line blocked." In the event that the signalman fails to move his hand-lever into its forward or blocking 60 position, during the time it remains unlocked by the action of the passing train, or before such train has passed by, it must remain locked in the backward position until released by the next succeeding train. The 65 semaphore will nevertheless be moved automatically into position to indicate "line blocked." A necessary result of this is, that

the lever cannot be moved so as to complete the electric circuit for transmitting an impulse to effect the clearing of the signal at 70 the station last passed, and this must, in such case, be done in some special way which may be provided for emergencies. Any negligence on the part of the signalman would therefore be immediately detected. The mechanism 75 for effecting these results will now be described: A rod F⁶ (Fig. 2) is attached to the bell-crank lever F³ and hence must partake of the movements of the hand-lever F⁵. Referring now to Fig. 8, it will be seen that this rod F⁶ is 80 connected to a slide F⁷ which moves in a guide-plate F⁸, (shown in plan in Fig. 8 and in cross-section in Fig. 7.) When the hand-lever F⁵ is in the position indicated by the dotted lines in Fig. 2, the bolt t will be thrust through the 85 coinciding bolt-holes t' in slide F⁷ and guide-plate F⁸, and the slide will be thereby securely locked. The unlocking of the slide F⁷ is effected by the action of the passing train, which depresses a pair of jointed treadle-bars, (shown 90 in Figs. 7 and 8) which treadle-bars, and their attachments, being essentially the same as those heretofore described and shown in Fig. 5, require no additional detailed description in this place. The treadle-bars referred to 95 are normally maintained in position to be actuated by the train, by a spring t². If desired, these treadle-bars may be made of sufficient length so that they will remain depressed during the time of passage of an entire train, it 100 being necessary only that they shall be able to engage any two of the successive wheels of a train at the same time. Other well-known retarding devices may be applied to the treadle-bars with like effect. 105

After the foregoing description, the mode of operation of the apparatus may more readily be understood by reference to Fig. 1. The diagram represents two complete block sections of a double-track railway, having three 110 signal-stations, designated respectively as B and D. The apparatus at station B is shown in its normal position, when no train is occupying either the block in advance or that in the rear. The hand-lever F⁵ is in position to hold the semaphore at "line clear" and is locked in such position by the bolt t at the same time causing the indicator k (Figs. 2 and 3) to exhibit the word "Clear" (referring to the condition of the track between B and C). 115 The indicator J at the same time exhibits the words "Train off," showing that the block from A to B is also clear. The apparatus at station C is however, represented in a different position, for the reason that a train X has 120 just passed station C and is now occupying the block between C and D. In passing the station at C it has unlocked the hand-lever, in the manner hereinbefore set forth, which lever has accordingly been shifted into the position shown. This movement of shifting the hand-lever performs three distinct operations: 125 First, changing the semaphore A to indicate "line-blocked;" second, changing the indicator 130

k from "clear" to "blocked," and third, closing a break in an electric circuit at the switch *U* for a purpose hereinafter explained. The action of the signalman, or the passage of the train over the treadle-bars, will have actuated the lever *B* at station *C*, thus raising the rod *r* and actuating the circuit-changer *R* (Figs. 1 and 5), thus temporarily transmitting a current from the battery *Z* (Fig. 1) through wires 1, 2 and 3 to the electromagnet *N* at station *D*, which attracts its armature and causes the latch *n* to release the indicator *J'*. This is at once drawn down by spring *j*² so as to display the words "Train on," thereby notifying the signalman at *D* that a train is approaching from *C*. When the train in its progress reaches station *D*, the hand-lever at that station is automatically unlocked, and the signals are shifted by the signalman by the series of operations already explained in connection with station *C*. It is also requisite that the signalman at *D* should unlock the hand-lever at station *C* in order that the signals at the last named point may be cleared. This is accomplished as follows:—The movement of the hand-lever at station *D* to block the line, completes an electric circuit at *U'* from battery *Z'* through electro-magnet *Y*, causing the latch *y'* to be withdrawn from hand-switch *y*. This switch is now thrown on contact *y*², after which, by depressing the key *T*, the signalman sends a current from battery *Z'* by way of circuit 4, 5, *y*, *y*², 6, *T*, 7, 2, *R* and 8 to switch *P*², and thence through electric alarm-bell or equivalent device *P* at station *C* and thence by wire 9 to the earth. As soon as the signalman at station *C* is thus notified by the alarm *P* that the train has passed station *D*, he turns the electric switch *p*, thus diverting the current from *D*, and causing it to pass through wire 10 and electro-magnet *M*. The latter, attracting its armature, withdraws the detent *m* from the tail of locking-lever *I'* (see Fig. 2) allowing the stop *I* to yield and permit the pin *h* of the hand-lever *F*⁵ to pass by, and the said lever to be moved into position to clear the signals. The same operation causes the projection *k'* upon the rod *K*³ to engage with the lever *J*, and thus restore the indicator *J'* attached thereto to its original position, indicating "line clear," where it is held as before by the detent *n*. The clearing of the signals requires the semaphore arm *A* to be lowered, and this is effected by the reverse rotation of the cam or eccentric *E* by means of the rack *E'*, and the coincident withdrawal of the stop *G*, by a gripper *H* attached to the rod *H'*, which latter rod receives its movement from the hand-lever *F*⁵ (see Fig. 4). This gripper is forced into place when the hand-lever is brought into a position corresponding with "line blocked," and upon the reverse movement of said lever, grasps a head *g*² attached by rod *g'* to stop *G*, and withdraws the latter from beneath the lever *B*, (thus leaving the latter free to move,) at the same time compressing the spring *g*. The jaws of the gripper are

made to separate when the rollers on their rear ends are forced inwardly by the incline *g*³, and are thus caused to release the stop *G*, which by the recoil of the spring *g* then resumes its original position as shown in Figs. 4 and 5, in readiness for a repetition of the operation.

Thus it will be understood that the organization of the apparatus is such that each signalman is notified when a train is approaching; that he cannot place his lever in position to enable him to release the signal at the next station in the rear, and permit it to be returned to "safety," until the train has reached the proper place in its progress, i. e. has gone the entire length of the block; that if he fails to set his signals, the operation will nevertheless be effected automatically by the action of the train on the treadle-bars; that after the line is blocked the signals are locked in a position indicating that condition; that the signals cannot be moved until after they have been unlocked by the action of the signalman at the next station in advance; and that the last named signalman cannot perform this act of unlocking until the train is under the protection of the next signal of the series.

I claim as my invention—

1. In a railway signaling apparatus, the combination of the visual train-signal; the hand-lever for shifting the same into either of two positions, and devices for locking said lever and signal in each of said positions; a mechanism mechanically actuated by the impact of a moving train for releasing one of said locks as the train enters the block guarded by said signal, and an electromagnetic apparatus for releasing the other of said locks when said train makes its exit from the block, substantially as set forth.

2. In a railway signaling apparatus, the combination of the visual train-signal; the hand-lever for shifting the same into either of two positions, a lock for retaining said lever and signal in position to indicate "clear," and a mechanism mechanically actuated by the impact of a moving train for releasing said lock as the train enters the block guarded by said signal, substantially as set forth.

3. In a railway signaling apparatus, the combination of the visual train-signal; the hand-lever for shifting the same into either of two positions; two guides or channels concentric with the center of movement of said hand-lever, connected at their respective ends by transverse channels; a pin affixed to said hand-lever and adapted to traverse said channels, and locking-dogs whereby said pin is forced to traverse said channels in opposite directions respectively, substantially as set forth.

4. In a railway signaling apparatus, the combination of the visual train-signal; the hand-lever for shifting the same into either of two positions; a bolt which normally locks said signal in position to indicate "clear;" a

5 treadle-bar capable of being depressed by the impact of a moving train; a mechanical connection from said treadle-bar for withdrawing said bolt, and a spring for restoring said treadle-bar and bolt to their normal position after the passage of a train, substantially as set forth.

5. In a railway signaling apparatus, the combination of the visual train-signal; the hand-lever for shifting the same into either of two positions; the rack, pinion and cam, receiving motion from said hand-lever and acting through a series of levers to move said signal into position indicating "line blocked," and a spring or springs for restoring said signal to its normal position without the assistance of said cam, substantially as set forth.

6. In a railway signaling apparatus, the combination of the visual train-signal; the hand-lever for shifting the same into position to indicate "line blocked;" the series of intermediate levers whereby motion is communicated from said hand-lever to said signal; and the spring-actuated stop for locking said series of levers and retaining said signal in position after the hand-lever has been withdrawn, substantially as set forth.

7. In a railway signaling apparatus, the combination of the visual train-signal; the hand-lever for shifting the same into position to indicate "line blocked;" the series of intermediate levers whereby motion is communicated from said hand-lever to said signal; the spring-actuated stop for locking said series of levers and retaining said signal in position after the hand lever has been withdrawn, and the detachable gripper by which said stop is withdrawn by a subsequent movement of said hand-lever, substantially as set forth.

8. In a railway signaling apparatus, the combination of the visual train-signal; the treadle-bar capable of being depressed by the impact of a moving train; a mechanical connection from said treadle-bar for moving said signal into position to indicate "line blocked;" and a hand-lever mechanically connected with said treadle-bar whereby it may be depressed and the signal moved into position, in advance of the automatic action thereupon of the moving train, substantially as set forth.

9. In a railway signaling apparatus, the combination of the visual train signal; the treadle-bar capable of being depressed by the impact of a moving train; a bolt which normally locks said signal in position to indicate "line clear;" a train-actuated device for automatically withdrawing said bolt, when the position of the signal is to be shifted, and a mechanical connection from said treadle-bar for moving said signal, when unlocked, into position to indicate "line blocked;" substantially as set forth.

10. In a railway signaling apparatus, the combination of the visual train signal; the hand-lever for shifting the same; the electric circuit-closer actuated by the movement of

said hand-lever for transmitting an electrical impulse to a distant station; an electro-magnet at said distant station which receives and is acted upon by said impulse, and a locked hand-lever for shifting the signal at said distant station, which is released by the action of said electro-magnet upon its lock, substantially as set forth.

11. In a railway signaling apparatus, the combination with the key or circuit-closer for transmitting an impulse for unlocking the distant signal, of the switch whereby said key is placed in circuit with the distant station, the visual train-signal at the home station; the hand-lever for shifting the same into a position to indicate "line blocked;" and a lock for said key-switch which is withdrawn by said hand-lever or signal when in said position, substantially as set forth.

12. In a railway signaling apparatus the combination of the visual train-signal; shifting mechanism for said signal capable of being actuated either manually or automatically upon the entrance of a train into the block-section guarded by said signal; an electric circuit-closer actuated by said shifting mechanism for transmitting an electric impulse in advance of a train to the next signal station in the series; a visual indicator at the last named station; and an electromagnet, which when energized by said impulse will cause said indicator to indicate the approach of such train, substantially as set forth.

13. In a railway signaling apparatus, the combination of the visual train-signal, the hand-lever for shifting the same into either of two positions; a lock for retaining said lever in position to indicate "line blocked;" an electromagnet for withdrawing said lock when energized by an electrical impulse; an alarm-bell actuated by an electro-magnet when energized by an electric current from a distant station, and a hand-switch whereby said current may be diverted from said alarm-bell to said unlocking magnet, substantially as set forth.

14. In a railway signaling apparatus, the combination of a treadle, a visual signal mechanically connected therewith and adapted to be moved into position to indicate "danger" or "line blocked" when said treadle has been depressed by the wheels of a moving train, a spring interposed in and forming part of said connection and adapted to receive the shock from the impact of a moving train upon said treadle, and by its recoil to move said signal to indicate "danger," and a mechanical stop which automatically acts to maintain both the treadle and the signal in the positions to which they have been moved by the passing train, until it is subsequently withdrawn by an independently acting force.

15. In a railway signaling apparatus, the combination of a treadle, a visual signal mechanically connected therewith and adapted to be moved into position to indicate "danger" or "line blocked" when said treadle has

been depressed by the wheels of a moving train, a spring interposed in and forming part of said connection, and adapted to receive the shock from the impact of a moving train upon said treadle, and by its recoil to move said signal to indicate "danger," a mechanical stop which automatically acts to maintain both the treadle and the signal in the positions to which they have been moved by the passing train, until it is subsequently withdrawn by an independently acting force, and

means for manually withdrawing said mechanical stop and returning said treadle and signal to their normal positions.

In testimony whereof I have hereunto subscribed my name this 13th day of April, A. D. 1892.

MURRAY CORRINGTON.
